US00D920120S

(12) **United States Design Patent** (10) **Patent No.:** **US D920,120 S**
(45) **Date of Patent:** **** May 25, 2021**

(54) **CONTAINER**

(71) Applicant: **Silgan Plastics LLC**, Chesterfield, MO (US)

(72) Inventors: **Alfred John Dunster**, Kelowna (CA); **James D. Janeczek**, Tecumseh, MI (US)

(73) Assignee: **Silgan Plastics LLC**, Chesterfield, MO (US)

(**) Term: **15 Years**

(21) Appl. No.: **29/732,384**

(22) Filed: **Apr. 23, 2020**

Related U.S. Application Data

(60) Division of application No. 29/691,109, filed on May 14, 2019, now Pat. No. Des. 896,652, which is a division of application No. 29/619,004, filed on Sep. 26, 2017, now Pat. No. Des. 853,846, which is a continuation of application No. 29/570,372, filed on Jul. 7, 2016, now Pat. No. Des. 801,819, which is a division of application No. 29/493,927, filed on Jun. 16, 2014, now Pat. No. Des. 763,698.

(57) **CLAIM**

We claim the ornamental design for a container, as shown and described.

DESCRIPTION

FIG. 1 is a front perspective view of embodiment one, of a container, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of embodiment two, of a container, showing our new design;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the figures illustrate the portions of the design that form no part of the claimed design.

The dot-dash broken lines immediately adjacent to the claimed areas in the views represent the boundaries of the design and form no part thereof.

None of the broken lines form any part of the claimed design.

1 Claim, 16 Drawing Sheets
